UNITED STATES PATENT OFFICE.

SAMUEL BUTTERWORTH, OF NEWTON, MASSACHUSETTS.

COLLAR-BUTTON.

1,374,355.

Specification of Letters Patent. Patented Apr. 12, 1921.

Application filed August 30, 1920. Serial No. 406,975.

To all whom it may concern:

Be it known that I, SAMUEL BUTTERWORTH, a citizen of the United States, residing at Newton, in the county of Middlesex 5 and State of Massachusetts, have invented new and useful Improvements in Collar-Buttons, of which the following is a specification.

This invention relates to collar buttons 10 for use at the back portion of a shirt neck band, to engage the back button-hole in the neck band and the back button-hole of a collar.

The chief object of the invention is to 15 provide a button adapted to have a minimum outward projection from the neck-band, and to permit the flap of a turn-down collar to stand close to the collar neck-band.

Another object is to provide a button 20 composed wholly of wire, and adapted to permit a neck-tie to slip freely between the neck-band and flap of a collar.

The invention is embodied in the improved button hereinafter described and 25 claimed.

Of the accompanying drawings forming a part of this specification,—

Figure 1 is a side view of the back portion of a shirt neck-band showing my im- 30 proved button partially engaged therewith.

Fig. 2 is a view similar to Fig. 1, showing the button engaged with the neck-band, but not in its operative position.

Fig. 3 is a view similar to Fig. 2, showing the button inverted from the position shown by Fig. 2, and in position to engage the neck-band of a collar.

Fig. 4 is a section on line 4—4 of Fig. 3.

Fig. 5 is a view similar to Fig. 3, showing a portion of a collar engaged with the head of the button, the flap portion of the collar being broken away.

Fig. 6 is a section on line 6—6 of Fig. 5, the flap portion of the collar being un- 45 broken.

Figs. 7 and 8 are respectively, a side view and an edge view of the button.

Figs. 9 and 10 are respectively sections on lines 9—9 and 10—10 of Fig. 1, the but- 50 ton being omitted.

The same reference characters indicate the same parts in all of the figures.

In the drawings, 12 represents the outer 55 ply and 13 the inner ply of a shirt neck-band, said plies being partially separated at the rear portion of the neck-band to form

the usual pocket 14 for the reception of a collar button foot, the outer ply 12 being provided with the usual button-hole 15, which receives the shank or neck of a collar 60 button.

My improved button is composed of a length of resilient wire having free ends and bent to form an elongated loop-shaped foot 16, formed to stand as shown by Fig. 65 4, between the plies 12 and 13, above the button-hole 15.

The wire is further bent to form the portions 17, 17, of a two-part neck, which is narrower than the length of the foot 16 and 70 in the same plane therewith. The wire is also bent to form the two parts 18 of a compressible head, the parts 18 being the free ends of the wire, and formed to project downwardly from the neck when the foot 75 and neck are in their operative positions, as shown by Fig. 4.

The head portions 18 diverge from the neck to the central portion of the head, and converge from said central portion to the 80 outer or lower extremity of the head, so that the outer portion of the head is wedge-shaped, and adapted to be compressed by contact with the ends of a button-hole, the neck being narrower than the central portion 85 of the head.

The button may be engaged with the ply 12 of the neck-band by, first, inserting one of the head portions 18 and a part of the other head portion in the button-hole 15, 90 as shown by Fig. 1, then swinging the button to the position shown by Fig. 2, the head projecting upward, and finally inverting the button so that the head projects downward, as shown by Figs. 3 and 4. The 95 foot 16 now stands between the neck-band plies 12 and 13, the neck passes through the button-hole 15 and the head projects downwardly from the button-hole and is slightly offset from the neck-band, the head-forming portions 18 being preferably curved from the plane of the foot and neck, as indicated by Figs. 4, 6 and 8. The head is now in position to engage the back button-hole 20 in the neck-band 21 of a turned-down collar, the flap of which is shown at 22.

The collar button-hole 20 is placed on the lower end of the head and the collar is moved upwardly until the button-head 110 passes through the button-hole 20, the ends of the button-hole first compressing the

head, as indicated by dotted lines in Fig. 7, and then permitting the head to expand, so that its central portion is wider than the length of the button-hole 20, as shown by 5 Fig. 5.

It will be seen that the button when in its operative position, does not form an objectionable protuberance at the outer side of the shirt and collar neck-bands, and that 10 the head is formed to permit a neck-tie to slip freely endwise between it and the flap portion 22 of the collar.

I claim:

A back collar-button composed of a 15 length of resilient wire having free ends, and bent to form an elongated loop-shaped foot formed to stand between the plies of the button foot-receiving pocket of a shirt neck-band, above a button-hole in one of

said plies, a two-part neck, narrower than 20 the length of the foot and in the same plane therewith, the neck being formed to enter said button-hole, and a two-part compressible head formed from the free ends of the wire and formed to project downwardly 25 from the neck when the foot and neck are in their operative positions, said ends diverging from the neck to the central portion of the head, and converging from said central portion to the outer extremity of 30 the head, so that the outer portion of the head is wedge-shaped, and adapted to be compressed by contact with the ends of a button-hole, the neck being narrower than the central portion of the head.

In testimony whereof I have affixed my signature.

SAMUEL BUTTERWORTH.
